[57] CLAIM

The ornamental design for a finger watch, as shown and described.

DESCRIPTION

FIG. 1 is a perspective view of a finger watch showing my new design;

FIG. 2 is a top plan view thereof;

FIG. 3 is a bottom plan view thereof;

FIG. 4 is a front elevational view thereof, the opposite elevation being a mirror image; and,

FIG. 5 is a left side elevational view thereof, the opposite side being a mirror image.

The broken line showing of a hand is illustrative of environment only and forms no part of the claimed design.
